UNITED STATES PATENT OFFICE.

SEWARD A. BULAND, OF LELAND, ILLINOIS.

HARNESS-HOOK.

1,174,051.

Specification of Letters Patent.

Patented Mar. 7, 1916.

Application filed April 16, 1915. Serial No. 21,703.

To all whom it may concern:

Be it known that I, SEWARD A. BULAND, a citizen of the United States, residing at Leland, in the county of La Salle and State 5 of Illinois, have invented a new and useful Harness-Hook, of which the following is a specification.

The device forming the subject matter of this application is adapted to be employed 10 for hanging up harness in a barn, for displaying merchandise, and under other circumstances which call for a vertically adjustable support which may be raised to dispose the merchandise or other articles carried thereby in an elevated and out of the 15 wav position.

The invention aims to provide novel means for raising and lowering the support and to 20 provide novel means for holding the support in adjusted vertical positions.

It is within the scope of the disclosure to improve generally and to enhance the utility 25 of devices of that type to which the present invention appertains.

With the above and other objects in view 30 which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing 40 from the spirit of the invention.

In the accompanying drawing: Figure 1 45 shows the invention in side elevation, parts being broken away; Fig. 2 is a cross section on the line 2—2 of Fig. 1; Fig. 3 is a cross section on the line 3—3 of Fig. 1.

In carrying out the present invention 50 there is provided a lateral support 1 which may be the wall of a building, an overhead support 2 being shown, the latter ordinarily constituting the ceiling. There is shown a vertical track 3 in the form of a rod or bar, the same, if desired, being provided at its 55 ends with angularly disposed legs 4 terminating in feet 5 bearing against the lateral support 1, the feet 5 being attached to the support 1 by means of securing elements 6 of any desired form. The track 3 is provided at points intermediate its ends with continuous, circumscribing shoulders denoted respectively by the reference characters 7 and 8.

Mounted to reciprocate vertically on the track 3 is a frame denoted generally by the numeral 9. The frame 9 is a composite structure and comprises a horizontally disposed upper arm 10, the rear end of which terminates in bifurcations 11 ordinarily constituting a part of an eye 12 surrounding the track 3. Mounted in the bifurcations 11 of the arm 10 is in axle 14 supporting a grooved wheel 15 adapted to engage one edge of the 60 track 3. Secured to and depending from the arm 10 is a downwardly and inwardly inclined brace 16, the lower end of which terminates in an approximately horizontal extension 17 having bifurcations 18 constituting 65 a part of an eye 19 receiving the track 3. Mounted in the bifurcations 18 is an axle 20 supporting a wheel 21. The wheel 21 bears against the opposite edge of the track 3 from that engaged by the wheel 15. 70

The bifurcations 18 which are formed at the lower end of the brace 16 support a pivot element 22 on which is fulcrumed intermediate its ends a dog 23, the lower end of which is curved toward the track 3 and is adapted 80 to coöperate therewith and, more specifically, coöperate with the shoulders 7 and 8. The upper end of the dog 23 terminates in an arm 24, extended rearwardly to a point beyond the track 3, the upper end of the 85 dog 23 being offset as clearly shown at 27 in Fig. 3, so that the extension or arm 24 may clear the track 3. Secured to the rear end of the arm 24 of the dog is a depending element 25 whereby the dog may be actuated. 90 A retractile spring 26 connects the upper end of the dog 23 with the brace 16. The bifurcations 18 at the lower end of the brace 16 are contracted as shown at 28, so that the dog 23 cannot have a movement longitudinally of the pivot element 22 and become accidentally disengaged from the shoulder 7 or the shoulder 8, the construction above described being such that, however, the eye 19 95 may be wide enough to receive the wheel 21. 100

Pivotaly connected at 30 with the arm 10 in front of the track 3 is a clevis 29. A pulley block 31 is pivotally connected as shown at 32 with the overhead support 2. One end of a flexible element 33 is secured to the clevis 29, the other end of the flexible element being carried upwardly through the pulley block 31 and thence being extended downwardly as clearly shown in Fig. 1 of the 105 drawings. 110

In Fig. 1 of the drawings, the frame 9 is shown in its elevated position, the lower end of the dog 23 being engaged with the shoulder 7. When it is desired to lower the frame 9, the flexible element 25 is pulled upon, the dog 23 tilting on its fulcrum 22, and the spring 26 being put under tension. Thereupon, the frame 9 may be lowered, the flexible element 33 being eased away and being paid out through the pulley block 31. When the frame 9 is in its lowermost position, the lower end of the dog 23 engages with the lower shoulder 8, it being noted that so soon as a pull upon the flexible element 25 is released, the spring 26 will react and will swing the lower end of the dog 23 inwardly so that the same bears against the periphery of the track 3, the lower end of the dog ultimately coming into contact with the shoulder 8 as the frame is lowered. Owing to the fact that the shoulders 7 and 8 extend entirely around the track 3, the frame 9 may be swung horizontally without causing a disengagement of the lower end of the dog 23 from either of the shoulders. The wheels 15 and 21 serve to guide the frame 9 in its vertical movement along the track 3 and facilitate such movement. Owing to the fact that the dog 23 is provided at its upper end with a rearwardly extended arm 24 which projects beyond the track 3, the flexible element 25 which controls the dog is always exposed and is not encumbered by articles of any sort which may be suspended from the arm 10.

Having thus described the invention, what is claimed is:—

1. In a device of the class described, an upright track; a frame mounted to reciprocate on the track; an upright dog pivotally mounted on the frame and including a rearwardly extended arm disposed transversely of the track; a depending operating element connected to the rear end of the arm; and a retractile spring forming a connection between the dog and the frame, the spring constituting means for maintaining the dog engaged with the track, and the track having a

shoulder with which the dog is adapted to coact.

2. In a device of the class described, an upright track; a frame comprising an upper arm, a lower arm and a brace connecting the arms; a wheel journaled for rotation on the upper arm and engaging one edge of the track; a wheel journaled for rotation on the lower arm and engaging the opposite edge of the track; and a movable dog carried by the lower arm, the track having a shoulder with which the dog is adapted to coöperate.

3. In a device of the class described, an upright track provided with a circumscribing shoulder; a frame mounted to slide longitudinally on the track and to rotate transversely of the track; a dog pivotally carried by the frame and adapted to coact with the shoulder; and spring means operatively connecting the dog with the frame and constituting means whereby the dog will be maintained in engagement with the track prior to the engagement with the dog and the shoulder, the dog being adapted to maintain its engagement with the shoulder under the actuation of the spring, when the frame is rotated transversely of the track.

4. In a device of the class described, an upright track; a frame comprising upper and lower arms and a brace connecting the arms, the arms receiving the track slidably; a dog fulcrumed intermediate its ends on the lower arm and having at its upper end a rearward extension prolonged beyond the track; depending actuating means connected with the rear end of the extension; a retractile spring forming a connection between the dog and the brace, the lower end of the dog being adapted to coact with the track, and the track having a shoulder with which the dog is adapted to coöperate.

In testimony that I claim the foregoing as my own, I have hereto affixed my signature in the presence of two witnesses.

SEWARD A. BULAND.
